(57) CLAIM

The ornamental design design for hand stitched double threaded raised seam leather jewelry, as shown and described.

DESCRIPTION

FIG. 1 is a perspective view of a hand stitched double threaded raised seam leather jewelry showing my new design;

FIG. 2 is a top plan view thereof;

FIG. 3 is a bottom view thereof;

FIG. 4 is a right side elevational view thereof;

FIG. 5 is a left side elevational view thereof;

FIG. 6 is an end elevational view thereof;

FIG. 7 is an opposite end elevational view thereof;

FIG. 8 is a perspective view thereof; and,

FIG. 9 is another perspective view thereof shown in an alternative environment.

The broken lines in FIGS. 8 and 9 are for illustrative purposes only and form no part of the claimed design.
